(57) **CLAIM**

The ornamental design for an armrest for a materials handling vehicle, as shown and described.

DESCRIPTION

FIG. 1 is a perspective view of a first embodiment of an armrest for a materials handling vehicle showing our new design;

FIG. 2 is a left side elevational view thereof;

FIG. 3 is a right side elevational view thereof;

FIG. 4 is a top view thereof;

FIG. 5 is a front elevational front view thereof;

FIG. 6 is a rear elevational view thereof;

FIG. 7 is a perspective view of a second embodiment of our new design;

FIG. 8 is a left side elevational view thereof;

FIG. 9 is a right side elevational view thereof;

FIG. 10 is a top view thereof;

FIG. 11 is a front elevational view thereof; and,

FIG. 12 is a rear elevational view thereof.

The bottom of both embodiments of the armrest is plain and unornamented.

UNITED STATES PATENT AND TRADEMARK OFFICE
CERTIFICATE OF CORRECTION

PATENT NO. : Des. 559,593 S
APPLICATION NO. : 29/223483
DATED : January 15, 2008
INVENTOR(S) : Todd M. Fullenkamp et al.

Page 1 of 1

It is certified that error appears in the above-identified patent and that said Letters Patent is hereby corrected as shown below:

In the Description:

“The bottom of both embodiments of the armrest is plain and unornamented” should read --The undersides of both embodiments are plain and unornamented.
The broken lines are for illustrative purposes only and form no part of the claimed design.--

Signed and Sealed this
